UNITED STATES PATENT OFFICE.

GUSTAV MEYER, OF GRANVILLE, ILLINOIS.

SEED-CORN BORER.

SPECIFICATION forming part of Letters Patent No. 307,672, dated November 4, 1884.

Application filed August 11, 1884. (No model.)

To all whom it may concern:

Be it known that I, GUSTAV MEYER, a citizen of the United States, residing at Granville, in the county of Putnam and State of Illinois, have invented a new and useful Improvement in Seed-Corn Hangers, of which the following is a specification, reference being had to the accompanying drawings.

My invention relates to a machine for stringing seed-corn upon the cob on a wire or cord for drying purposes; and it has for its object to provide a device of this character which shall be cheap and simple in its construction, effective in its operation, and one that will be strong and durable.

With these ends in view the invention consists in the improved construction and combinations of parts, hereinafter fully described, and pointed out in the claims.

In the drawings, Figure 1 is a perspective view of a machine constructed in accordance with my invention. Fig. 2 is a modification of the same. Fig. 3 is another modification, and Fig. 4 is a view of the rod for stringing the corn.

In the accompanying drawings, in which like letters of reference indicate corresponding parts in all the figures, A represents the frame, having at its lower end a bracket, B, which is provided with a screw-threaded opening, a, in which is seated a set or thumb screw, b. It will be seen that by this arrangement the bracket B may be engaged with the edge of a table or bench, and held securely in place thereon by means of said thumb-screw.

C represents a shaft which is mounted in the sides of the frame A, about midway the length of the same. Upon one end of this shaft, outside the frame A, is mounted a gear-wheel, D, which is provided with an operating crank or handle, E.

F represents a spoon-bit having an extended shaft at its end. This shaft extends through the sides of the frame, at the upper end thereof, and upon the end of the bit, outside of the frame, is mounted a pinion, G, which gears with the wheel D. A spool, H, incloses the shaft of said bit, its ends bearing

against the inner sides of the frame. The bit-shaft is held against lateral movement by means of a transverse pin passing through said shaft outside of the frame, which holds the bit in place.

In Fig. 2 I have shown a modification in which the gear-wheels are dispensed with. In this case I connect an operating crank or handle directly to the bit-shaft. Fig. 3 illustrates another modification. In this case I attach a stock, I, to the shaft of a grindstone, preferably one that is operated by foot-power. This stock has a squared opening to fit upon said shaft, and communicating with said opening is a set-screw which clamps or bites the grindstone-shaft and holds the stock in place. There is also a square or rectangular opening at the other end of the stock, said opening being adapted to receive the end of the bit, and communicating with this opening is another set-screw which bites the bit and holds it in place.

The operation is as follows: The ear of corn is held in the hand, with the butt to the point of the bit, and upon said bit being operated it will enter the cob of the ear and bore a hole longitudinally through the said cob. As soon as the ear of corn has been bored, it is strung upon a wire or cord. To string the corn I employ a rod having a handle at its upper end and a point or barb at its lower end. I push said rod through the cob, and hook the wire or cord on the end of the rod and then draw it through.

It will be seen that a machine constructed in accordance with my invention is simple in its construction, may be manufactured and supplied at a slight cost, and that by its use corn may be readily and quickly strung for drying purposes.

Having fully described my invention, what I claim as new, and desire to secure by Letters Patent, is—

1. The combination of a suitable frame having a bracket, B, a gear-wheel mounted in said frame, a shaft mounted at the end of said frame, and a pinion mounted on said shaft outside the frame, said shaft being extended to form an auger, as set forth.

2. The combination, with a suitable frame having a clamping-bracket for its attachment, a shaft mounted about midway the length of said frame, and a gear-wheel mounted on 5 said shaft, of an auger having an extension or shaft, a pinion mounted on the end of said shaft, and a sleeve inclosing said shaft inside the frame, substantially as set forth.

In testimony that I claim the foregoing as my own I have hereto affixed my signature in presence of two witnesses.

GUSTAV MEYER.

Witnesses:

C. K. WAN,
JOHN GEHM.
